United States Patent Office.

O. P. McDONALD, OF CARBONDALE, ILLINOIS.

Letters Patent No. 77,504, dated May 5, 1868.

IMPROVEMENT IN ATTACHMENTS FOR PENDULUM-CLOCKS.

The Schedule referred to in these Letters Patent and making part of the same.

TO ALL WHOM IT MAY CONCERN:

Be it known that I, O. P. McDONALD, of Carbondale, in the county of Jackson, and State of Illinois, have invented a new and improved Compensation-Attachment for Pendulum-Clocks, &c.; and I do hereby declare that the following is a full, clear, and exact description thereof, which will enable others skilled in the art to make and use the same, reference being had to the accompanying drawings, forming part of this specification.

The present invention relates to an attachment to the ordinary pendulum-rods of clocks and other similar time-movements, by which the effective suspension-point of the pendulum is made to move up and down, just as the pendulum-ball moves up and down, by the contraction or expansion of the pendulum-rod, without making any alteration on the pendulum or its ordinary appendages.

The above result is effected by the unequal expansion of different metals or other equivalent materials, as and in a manner to be now described, reference being had to the accompanying plate of drawings, in which—

Figure 1 is a front or face view of the pendulum and its suspension parts, and

Figure 2 an edge view thereof.

Similar letters of reference indicate corresponding parts.

A and B, in the drawings, represent two small rods or wires, the one, A, made of steel, and the other, B, of zinc. Both rods, A and B, are flattened at one end, with a file or other suitable means, so that when placed within their flattened surface together, a thread may be cut around them, and a tap or nut, C, applied, to hold them firmly together at such ends.

The zinc rod B is flattened at its upper end, and provided with a collet, a, fitting upon the short stud e, secured to the cross-bar D of the frame carrying the clock-movement. The steel rod A is also flattened at its upper end, and bent at a right angle to its length, with a fine slit or slot, b, in the end, c, for the pendulum-rod to pass through, as seen in the drawings; f being the point of suspension. The steel rod A is also provided with a projection, a', near the upper end of its vertical portion, through which the zinc rod B passes, in such a manner as to steady it, but not hold it rigidly.

The lower ends of the rods A and B pass through an opening, E, formed in a horizontal arm, F, secured to the back of the clock. The hole should be sufficiently large to permit the rods to move freely through it, while at the same time the arm F acts as a guide to prevent the rods from vibrating with the pendulum. G is a nut, placed upon the rods A B, either above or below the arm F, but not in contact with it; its object being to regulate the expansion of the steel rod, which is effected by running the nut G up or down upon the rods A and B. The zinc rod B should be sufficiently long to compensate for the steel rod A and the pendulum-rod.

The operation is as follows: As the zinc rod is expanded or contracted, it carries with it the steel rod, whose end, c, moves upon the pendulum-rod, and becomes in effect the suspension-point; for example, in expanding, the zinc rod is moved downward from the collet a, carrying with it the steel rod. The latter having its lower end secured by the nut G and its upper end guided by the zinc rod, expands in an upward direction, moving the arm e upon the pendulum-rod, and thereby maintaining a uniform point of suspension, as the steel rod compensates for the expansion or contraction of the zinc rod and pendulum-rod.

Although I have herein mentioned steel and zinc as the two metals used, I do not intend to confine myself to them or to any two other particular metals or other materials, reserving to myself the right to use any two substances which will produce the desired effect.

I claim as new, and desire to secure by Letters Patent—

The combination of the rods A B, of different metals, having unequal expansibility, with the pendulum-rod of a clock, substantially as and for the purpose specified.

O. P. McDONALD.
